United States Patent Office.

BENJAMIN L. SOUTHACK, OF NEW YORK, N. Y.

Letters Patent No. 73,845, dated January 28, 1868.

IMPROVED RECLINING-CHAIR.

The Schedule referred to in these Letters Patent and making part of the same.

TO ALL WHOM IT MAY CONCERN

Be it known that I, B. L. SOUTHACK, of the city, county, and State of New York, have invented a new and improved Reclining-Chair; and I do hereby declare that the following is a full, clear, and exact description thereof, which will enable others skilled in the art to make and use the same, reference being had to the accompanying drawings, forming part of this specification.

This invention relates to a new and improved chair of that class which are provided with a movable hinged back and foot-piece, connected together and arranged in such a manner that a person occupying the chair may convert the same from an upright-sitting to a reclining-chair.

My invention consists in a novel manner of constructing and arranging the several parts, whereby chairs of this class may be very much reduced in the cost of manufacture, far more simple in construction, and less liable to get out of repair than those now in use. In the accompanying sheet of drawings—

Figure 1 is a side sectional view of my invention, taken in the line $x x$, fig. 2.

Figure 2, a plan or top view of the same, partly in section.

Similar letters of reference indicate corresponding parts.

A represents the seat of the chair, which is supported by legs a , the legs and seat being permanently attached or connected together. The seat may be provided with arms B at its sides. C represents the back of the chair, which is connected by hinges a' to the rear end of the seat A. The lower end of the back, C, projects down below the seat A, as shown clearly in fig. 1. D represents a foot-piece, which is attached to the lower end of a leg-piece, E, at right angles, the upper end of the latter being attached to the front end of the seat A by hinges b . The lower end of the back, C, and the upper part of the leg-piece E, are connected below the seat A by a bar, F, the ends of which are attached to the back and leg-piece by hinges c .

By this arrangement it will be seen that the back and leg-piece are made to move simultaneously, the leg-piece moving upward when the back is moved backward. The bar F is provided at its upper surface with a rack, G, into which a pawl, H, catches, said pawl being attached to the under side of the seat A by a hinge or joint, d. This pawl H prevents the back, C, from moving outward or backward, and the leg-piece E from rising when not required, holding said parts when the person occupying the chair prefers to be in a more or less reclining position. The leg-piece may be lowered, and the back, C, raised, however, by the occupant simply assuming an upright position, with his legs bearing against the leg-piece E; and when a reclining position is required, the pawl H is moved up out of rack G, by means of a bent lever, I, arranged in any suitable way.

It will be seen that this chair may be very cheaply constructed, as the arrangement of the parts is extremely simple, and there is no mechanism liable to get out of repair. It also may be upholstered without any difficulty whatever, and this is an important feature of the invention, for this class of chair upholstery, if not properly fitted, soon becomes cut and worn under the movement of the working parts.

I claim as new, and desire to secure by Letters Patent—

A reclining-chair, constructed as described, and consisting of the fixed seat A, hinged back C, and leg-piece E D, hinged rack-bar F G, pawl H, lever I, legs a , arms B, and hinges $a' b c c$, all arranged and operating as described and for the purpose specified.

BENJ. L. SOUTHACK.
